United States Patent Office

Des. 183,851
Patented Nov. 4, 1958

183,851

RELIGIOUS PLAQUE

Louis F. Mancini, Baltimore, Md.

Application August 13, 1957, Serial No. 47,355

Term of patent 14 years

(Cl. D29—23)

FIG. 1

FIG. 2

FIG. 3

Fig. 1 is a front elevational view of a religious plaque showing my new design;

Fig. 2 is a rear elevational view thereof; and

Fig. 3 is a top plan view thereof.

The dominant features of my design reside in the portion shown in full lines.

I claim:

The ornamental design for a religious plaque, substantially as shown and described.
